UNITED STATES PATENT OFFICE.

OSBORNE H. SHEPPARD, OF CHICAGO, ILLINOIS.

WINDOW-BURGLAR-PROOFING DEVICE.

1,079,029.

Specification of Letters Patent.

Patented Nov. 18, 1913.

Application filed July 21, 1913. Serial No. 730,215.

To all whom it may concern:

Be it known that I, OSBORNE H. SHEPPARD, a citizen of the United States, residing at Chicago, in the county of Cook and State of Illinois, have invented a new and useful Improvement in Window-Burglar-Proofing Devices, of which the following is a specification.

My invention relates to an improvement 10 in the class of devices used for obstructing the upper and lower sashes of windows, when partly opened for ventilation, against being farther opened sufficiently to permit entry through the opening into the inclosure 15 to be protected.

A device of the kind referred to, and upon which, particularly, it is my object to improve with a view to increasing its safety, resembles a hinge having two pintle-connected leaves. One leaf is adapted to be fastened to the inner face of a side rail of the upper sash, and the other leaf folds against it when it is desired to leave the sashes free to be opened. The device is 25 thus fastened at a sufficiently low point on the upper sash, so that when the free leaf is turned to extend at an angle to the fastened leaf to project into the path of the upper rail of the lower sash, it will act as a 30 stop against raising the latter and lowering the upper sash farther than is required for ventilation, but not far enough for the entry of a burglar through either opening. The device is further provided with latching-means for locking the swinging leaf in 35 its stopping position. This device does not afford an adequate degree of safety, however, because it is a comparatively easy matter to reach it from the outside, either 40 through the openings afforded by the partially-opened sashes, or through an opening cut in the window-glass, to unlock the latch, when the stop-leaf may be readily turned aside to permit farther opening of the window.

My improvement is designed to overcome this objection and increase the safety function of the device.

In the accompanying drawing, Figure 1 50 is a broken perspective view showing my improved device in its operative position; Fig. 2 is an inner face view of the device, showing the hinge-leaves spread apart to their fullest extent; Fig. 3 is a similar view of the 55 same showing the swinging hinge-leaf extending at right-angles to the fixed leaf, and

Fig. 4 is an enlarged broken section on line 4, Fig. 2.

A hinge 5, of suitable size, comprises two leaves, 6 and 7, one of which is shown to be 60 provided with holes, through which to screw or nail it to a side-rail of an upper window-sash 8, as represented in Fig. 1. The other, swinging, leaf may be imperforate, except for a single hole, in which works a removable stop, shown in its preferred form of a set-screw 9; this being the gist of my improvement. On the inner face of the swinging leaf is fastened a wire spring 10 having a flattened, or knife-edge section 11, and 65 projecting beyond the outer edge of the leaf to afford a handle 12. The spring extends above the set-screw, close to the face of the leaf, so that when the screw is adjusted the flat spring-section 11 engages its thread 70 close to the leaf-surface and locks the set-screw against longitudinal movement.

With the device secured in place on the upper window-sash, and the set-screw removed, the swinging leaf may be folded 80 against the fastened leaf to present no obstruction to raising the lower sash or lowering the upper one to the full or to any desired extent. To set the device for performing its burglar-proof function, the set-screw 85 is inserted into the hole provided for it in the swinging leaf. The inner end of the set-screw then will abut, in any attempt to fold the leaf 7 against the adjacent face of the fastened leaf, and prevent removal of 90 the swinging leaf out of the path of the lower sash, and the outer end of the set-screw prevents turning the swinging leaf outwardly to take it out of that path, since that end will strike the inner side of the 95 window-frame in any attempt to do so, thereby insuring the projection of the swinging leaf, as a stop, over the path of the upper rail of the lower sash, to prevent raising it unduly high and lowering the upper 100 sash to an undue extent. In adjusting the set-screw into its operative position, the spring 10 is held raised to separate it from the threads, and when the stop is properly adjusted the spring is released to engage a 105 thread and lock the stop; and the latter may be readily withdrawn, at the inner side of the window, to render the device inoperative for its purpose, upon straining the spring out of contact with the threads and holding 110 it there pending the withdrawal.

The spring lock for the stop 9 is an ad-

2
junct in enhancing security of the device against tampering, because a burglar working from the outside through the partially-opened window, or through a hole made for the purpose in the window-pane, can not well use more than one hand. With his one hand he might, in the absence of the spring-lock, succeed in withdrawing the set-screw, though the attempt would be attended with great difficulty in manipulating it, at its head, in the narrow space between the swinging leaf and the adjacent face of the window-frame. However, with the spring in operation he could not, with one hand, hold it out of engagement with the stop-threads and at the same time manipulate the stop to remove it; so that the attempt would be wholly frustrated.

What I claim as new and desire to secure 20 by Letters Patent is—

1. A device of the character described, comprising a hinge having a leaf adapted to be fastened to an upper window-sash, and the other, swinging, leaf to be folded, at will, 25 against the fastened leaf or projected at an angle thereto into the path of the lower sash, and a stop projecting transversely through the swinging leaf, for the purpose set forth.
2. A device of the character described, comprising a hinge having a leaf adapted to be fastened to an upper window-sash, and another, swinging, leaf to be folded, at will, against the fastened leaf or projected at an 35 angle thereto into the path of the lower sash, and a removable stop passing transversely through the swinging leaf and projecting at opposite sides thereof, for the purpose set forth.
3. A device of the character described, comprising a hinge having a leaf adapted to be fastened to an upper window-sash, and another, swinging, leaf to be folded, at will, 40

against the fastened leaf or projected at an angle thereto into the path of the lower sash, 45 and a set-screw working through the swinging leaf, for the purpose set forth.

4. A device of the character described, comprising a hinge having a leaf adapted to be fastened to an upper window-sash, and another, swinging, leaf to be folded, at will, against the fastened leaf or projected at an angle thereto into the path of the lower sash, a threaded stop working through the swinging leaf, and a lock on the swinging leaf 55 releasably engaging the stop-thread, for the purpose set forth.

5. A device of the character described, comprising a hinge having a leaf adapted to be fastened to an upper window-sash, and another, swinging, leaf to be folded, at will, against the fastened leaf or projected at an angle thereto into the path of the lower sash, a set-screw working through the swinging leaf, and a spring supported on the swinging 65 leaf to normally engage the thread of and lock the set-screw against withdrawal, for the purpose set forth.

6. A device of the character described, comprising a hinge having one leaf adapted to be fastened to an upper window-sash, and another, swinging, leaf to be folded, at will, against the fastened leaf or projected at an angle thereto into the path of the lower sash, a set-screw working through the swinging 75 leaf, and a wire spring fastened to a face of the swinging leaf and having a section normally engaging, releasably, the thread of said screw to lock it against withdrawal, and a handle on the spring, for the purpose set 80 forth.

OSBORNE H. SHEPPARD.
